UNITED STATES PATENT OFFICE.

ALBERT H. KIPPENBERG, OF PITTSBURGH, PENNSYLVANIA.

JAR-CLOSURE.

1,300,736.

Specification of Letters Patent. Patented Apr. 15, 1919.

Application filed November 8, 1916. Serial No. 130,152.

To all whom it may concern:

Be it known that I, ALBERT H. KIPPENBERG, a citizen of the United States, residing at Pittsburgh, in the county of Allegheny, and State of Pennsylvania, have invented a new and useful Improvement in Jar-Closures, of which the following is a full, clear, and exact description, reference being had to the accompanying drawings, forming part of this specification, in which—

Figure 1 is a vertical section through the jar and closure.

Fig. 2 is a fragmentary vertical section through the jar with the closure cap removed.

Fig. 3 is a fragmentary elevation of the top of the jar.

Fig. 4 is a horizontal section, on the line IV—IV of Fig. 3, and

Figs. 5 and 6 are vertical sections through the jar and cap, respectively, showing a modification.

The present invention relates to jar closures. The object of the invention is to produce a cheap and practical jar closure that will not leak, and which can be quickly applied and readily removed.

Referring to the drawings, in which is illustrated the preferred embodiment of the invention, a jar 2, preferably a glass fruit jar, is provided with two beads 3 and 4 around its neck at the mouth forming a ring receiving groove 5 between such beads. Above the beads is a substantially cylindrical gasket receiving face 6 which as shown in Figs. 1 to 4 is on the outside of the jar mouth. This gasket-receiving face may be formed on the inside of the mouth as shown at 6^a in the modification shown in Fig. 5.

An expanding ring 10 of resilient wire is fitted in the groove 5. The bottom bead 3 of the groove 5 is cut away at 11 to leave space through which the handles 12 of the wire ring may project downwardly. The opposite side of the groove 5 is provided with a recess 13 into which fits an inwardly projecting bend 14 in the spring ring 10 for the purpose of centering the ring. A cap 20 is applied over the mouth of the jar as shown in Fig. 1. The cap 20 is preferably made of stamped metal or any other suitable and cheap material. This cap 20 has an outwardly flared bottom edge 21 which, when the cap is pressed down over the jar, engages and compresses the expansion ring 10. As shown in Figs. 3 and 4, the ring

is held centered so that the outwardly bowed side portions of the ring extend out from the groove 5 an equal amount on both sides of the jar, and not too far for the flared bottom 21 of the cap to engage and press them in when the cap is pushed down into place. This centering is accomplished by the engagement of the ring and the jar at both the front and the back thereof so as to securely keep the ring from being displaced sidewise. The ring is held against sidewise displacement at the back by means of the notch 13 and bend 14, and at the front by the engagement of the bent down handle portions 12 with the ends of the bead 3. As shown in Figs. 3 and 4, when the cap is removed the turned down handle portions 12 of the ring lie against the front ends of the bead at the sides of the cut away space 11. This engagement of the handles with the ends of the bead prevents the front of the ring from being displaced sidewise from its position as shown in Figs. 3 and 4 of the drawings. This front and back engagement accurately spaces the outwardly bowed side portions of the ring so that when the cap is applied, the ring does not have to be manipulated to properly position it, but the cap can be simply pressed down on the jar, the ring being in position to be engaged by the flange 21 and automatically compressed. While this is of aid in the rapid hand sealing of jars, it is particularly important in machine sealing where the caps are applied and pressed down by a machine.

As can readily be seen from the drawings, if it were not for the engagement of the jar and ring at both the front and back thereof, the ring could be displaced sidewise so that one bowed side portion would project too far out to fit within and be readily compressed by the flared edge of the cap when the cap is applied. An inwardly facing groove 22 is formed in the cap 20 to register with the groove 5 in the jar when the cap is in place. When the cap is pushed in place the expansion ring 10 expands and portions of it fit into the groove 22, while other portions fit in the groove 5, thus locking the cap firmly in place. Above the groove 22 is an inwardly formed bead 23 which forms a gasket-engaging face pressing against the outside of the rubber gasket 24 when the cap is in place, and thus forming a hermetic seal. While, as shown

in Fig. 1, the gasket-receiving face on the cap fits on the outside of the gasket, the cap may be formed so that the gasket-receiving face of the cap is on the inside of 5 the gasket as shown in Fig. 5, in which the top of the cap is indented to form an outwardly extending gasket-receiving face 23^a, by means of which the gasket 24 is pressed out against the gasket-receiving face 6^a on 10 the jar. By forming the gasket-receiving face on the jar substantially cylindrical so that the cap fits either around it or inside of it, a stopper effect is obtained which has been found to be very effective in insuring 15 a hermetic seal. Moreover, this stopper-like action tends to frictionally hold the cap in place so that under some conditions, as, for example, where the goods are not pasteurized, it may be possible to omit the retaining ring 10 and rely upon the friction of 20 the cylindrically disposed gasket to retain the cap in place.

The spring ring 10 is applied to the jar as shown in Figs. 2, 3 and 4, the opposite 25 portions of the ring projecting out of the groove 5, while the portions of the ring next to the handles 12 and the bend 14 fit tightly in the groove 5. When the cap is applied it is pressed down, the flanged or 30 bell-mouthed portion 21 of the cap engaging the ring and pressing it in, until the cap is pressed into place where the groove 22 matches with the groove 5, whereupon the expansion ring will expand into place in the 35 groove 22, positively locking the cap in place. The handles 12 will spring apart when this occurs, thus indicating to the operator that the cap is locked. When the cap is being pressed into place the gasket 40 24 is compressed between the gasket-receiving faces on the jar and cap and forms a hermetic seal. When the cap is to be removed the handles 12 are pressed together, thus freeing the groove 22 of the expansion 45 ring and permitting the removal of the cap. The cap is easily applied, it being necessary only to push the cap down in place to insure a perfect air-tight hermetic seal. The cap is also easily removed, it being necessary 50 only to compress the wire by means of the handles 12.

While the jar closure is intended primarily to be used by manufacturers, it nevertheless is well adapted for domestic use. 55 Where the goods are put up under a vacuum, no external means are necessary to hold the caps in place while the vacuum sets, because as soon as the cap is pressed into place the spring ring retains it firmly in place while 60 the contents cool and a vacuum is formed under the cap. Moreover, the spring ring 10 will retain the cap firmly in place, even if the vacuum is broken, and thus prevent goods spilling or leaking in transit. The 65 jar mouth and neck are easily formed with-

out any complicated set of molds. The cap can be readily and cheaply pressed out of sheet metal, and the ring can be cheaply manufactured.

While the preferred embodiment of the invention has been specifically illustrated and described, it is to be understood that the invention is not limited to the illustrated details of construction, but may be embodied in other constructions of jars and closures 75 within the scope of the following claims.

I claim:

1. The combination of a jar having a circumferential groove at its mouth, a cap having a groove registering with the groove in 80 the jar, and a resilient wire expansion ring received in both grooves for locking the cap on the jar, and having projecting handles external to the jar for contracting the ring to permit the removal of the cap, and also 85 having an inwardly projecting bend engaging a recess in the jar so as to be kept from sidewise movement therein to assist in centering the ring, substantially as described.

2. The combination of a jar having a 90 circumferential groove at its mouth which has its lower wall cut away at one place, a cap having an unbroken downwardly depending flange extending over the lower wall of the groove and having a groove registering with the groove in the jar, and a resilient wire expansion ring received in both grooves for locking the cap on the jar and having handles downwardly projecting through the cut away wall of the jar groove 100 95 below the edge of the cap for contracting the ring to permit the removal of the cap, substantially as described.

3. The combination of a jar having a circumferential groove at its mouth, a cap 105 having an oppositely facing groove registering with the groove in the jar, a resilient wire expansion ring received in both grooves for locking the cap on the jar, said ring being normally held in the groove on 110 the jar when the cap is removed and means engaging the ring for centering it when the cap is removed, substantially as described.

4. The combination of a jar having a circumferential groove at its mouth, a cap having an oppositely facing groove, a resilient wire expansion ring received in both grooves for locking the cap on the jar, and means 120 engaging the ring at both the front and back thereof and preventing sidewise displacement thereof for centering it when the cap is removed, said cap having a flared mouth for engaging and contracting the centered ring when the cap is pressed down 125 on the jar, substantially as described.

5. The combination of a jar having an outwardly facing circumferential groove and a substantially cylindrical gasket-receiving face between the groove and the jar 130

5 mouth, a cap having an inwardly facing co-operating circumferential groove and a gasket-receiving face registering with the gasket-receiving face of the jar, a sealing gasket compressed between the gasket-receiving faces of the jar and cap, and a resilient wire expansion ring received in both grooves for locking the cap on the jar, said ring being normally held in the groove on 10 the jar when the cap is removed, substantially as described.

6. The combination of a jar having a circumferential groove at its mouth, a cap having an oppositely facing groove, a resilient wire expansion ring received in both 15 grooves for locking the cap on the jar, handles for contracting the ring on the front thereof, means engaging the handles to prevent sidewise displacement thereof when the 20 cap is removed, an inwardly extending projecting carried by the ring and engaging a recess in the jar so as to be kept from sidewise displacement when the cap is removed, said ring when the cap is removed, resiliently engaging the jar at the front and back thereof 25 but having its side portions extending from the groove; substantially as described.

7. The combination of a jar having a circumferential groove at its mouth, a resilient 30 wire expansion ring held in said groove and adapted to retain a cap in position on the jar, said ring resiliently pressing against the jar at the front and back thereof and

projecting from the groove at the sides thereof, and means on the jar engaging the 35 ring at the front and back where it is pressed against the jar for preventing bodily sidewise displacement thereof; substantially as described.

8. The combination of a jar having a circumferential groove at its mouth, a cap having an annular downwardly depending flange with an oppositely facing groove therein and having a flared mouth, a resilient wire expansion ring received in both 45 grooves for locking the cap on the jar, said ring, when the cap is removed, resiliently engaging the jar at the front and back thereof and having its side portions projecting from the groove so as to be engaged 50 and contracted by the flared mouth of the cap when the cap is applied to the jar, and means on the jar engaging the ring at the front and back thereof for preventing bodily sidewise displacement thereof, whereby the 55 projecting side portions may always project substantially equal distances from the jar when the cap is removed; substantially as described.

In testimony whereof, I have hereunto 60 set my hand.

ALBERT H. KIPPENBERG.
